UNITED STATES PATENT OFFICE.

PERCY S. BAILEY, OF MARBLEHEAD, MASSACHUSETTS, ASSIGNOR TO GENERAL ELECTRIC COMPANY, A CORPORATION OF NEW YORK.

DESIGN FOR A REFLECTOR.

Application filed June 29, 1926. Serial No. 18,208. Term of patent 14 years.

To all whom it may concern:

Be it known that I, PERCY S. BAILEY, a citizen of the United States, residing at Marblehead, in the county of Essex, State of Massachusetts, have invented a new, original, and ornamental Design for a Reflector, of which the following is a specification, reference being had to the accompanying drawing, forming a part thereof.

In the drawing Fig. 1 is a perspective view from below of the ornamental reflector of my invention, showing principally the

forward half portion of the reflector. However, both the forward and the rear portions of the reflector are the same. Fig. 2 is a perspective view of the same device from above.

I claim:

The ornamental design for a reflector as shown.

In witness whereof I have hereunto set my hand this 26th day of June, 1926.

PERCY S. BAILEY.
